DESIGN FOR A TOY STABLE

Walker W. Tackett, North Hollywood, Calif.

Application July 5, 1944, Serial No. 114,321

Term of patent 3½ years

(Cl. D34—15)

To all whom it may concern:

Be it known that I, Walker W. Tackett, a citizen of the United States, residing at North Hollywood, in the county of Los Angeles and State of California, have invented a new, original, and ornamental Design for a Toy Stable, of which the following is a specification, reference being had to the accompanying drawings, forming a part thereof.

Fig. 1 is a front perspective view of a toy stable showing my new design.

Fig. 2 is a rear perspective view, on a somewhat larger scale, of the stable.

I claim:

The ornamental design for a toy stable, as shown.

WALKER W. TACKETT.
